UNITED STATES PATENT OFFICE

2,318,351

SHAYER

Adalbert Alexay, Schenectady, N. Y., assignor to
 General Electric Company, a corporation of
 New York

Application December 16, 1942, Serial No. 469,206

4 Claims. (Cl. 30—43)

The present invention relates to shavers of the type having an outer cutting head provided with spaced hair-receiving openings and an inner cutter for shearing hair projecting through the openings. In such shavers only part of the cutting head is open to receive hair, and to perform a thorough shaving operation it is necessary that the user repeatedly move the head back and forth over the skin surface.

The object of my invention is to provide an improved shaver in which the cutting head is given a power operated scanning movement so as to expose all parts of the skin surface beneath the cutting head to the shaving action.

For a consideration of what I believe novel and my invention, attention is directed to the following description and the claims appended thereto.

In the accompanying drawing, Fig. 1 is a sectional front elevation of a shaver embodying my invention; Fig. 2 is a sectional side elevation; and Fig. 3 is an end view of the cutting head partly broken away.

Referring to the drawing, there is shown a shaver having a split casing comprising parts 1 and 2 clamped together by screws 3. Within the lower end of the casing is an electric motor having a shaft 4 driving a transversely extending cam shaft 5 through bevel gears 6 and 7 and driving longitudinally extending shafts 8 through reduction gearing 9, 10. The cam shaft 5 is journaled in bosses 11 and carries cams 12 cooperating with forked ends 13 of rocker arms 14 pivoted on pins 15 extending between bosses 16. The shafts 8, which rotate at a slower speed than the cam shaft, are journaled in bosses 17 and at the upper ends are provided with integral eccentrics 18 journaled in struts 19 at the lower end of a cutting head 20.

The cutting head is made of thin sheet steel folded in a U shape with the arms of the U fixed to the struts 19 and the base of the U provided with narrow hair-receiving openings or slots 22. The slot width is dependent upon the thickness of the metal from which the head is formed and is such that the skin bulges slightly into the slots but does not project below the inner or shearing surface of the head. If sheet metal of a thickness of from .002" to .004" is used for the head, the slots may be from .007" to .010" wide.

Within the cutting head are longitudinally sliding cutters each of which comprises a base 23 guided on the sides of the cutting head, and upstanding blades 24 bearing against the inner

or shearing surface of the cutting head. The cutters have a ball and socket connection 25 with the upper ends of the rocker arms 14 and are held against the inner surface of the cutting head by compression springs 26 on the arms 14. The ball and socket connection between the rocker arms and the cutters permits tilting of the cutters so as to maintain the upper edges of the blades 24 in contact with the inner surface of the cutting head throughout the life of the shaver. If all of the blades were rigidly mounted in a single bar there would be a tendency for the head and blades to wear at the center where most of the shaving is done, resulting in a clearance which would decrease the effectiveness of the shearing action.

The cutting head is surrounded by a guard 27 fixed to the casing and having caps 28 enclosing the ends of the cutting head and elongated combs 29 extending along each side of the cutting head. The combs have spaced teeth 30 with outer ends 31 shaped to lift hair off the surface of the skin and guide it to the cutting head, and with inner ends 32 spaced from and overlying the lateral edges of the cutting head. As the shaver is moved back and forth both the outer and inner ends of the teeth of the comb tend to lift hair off the skin surface so that it will be guided into the slots in the cutting head. The springs 26 urge the cutting head into shearing engagement with the combs 29.

In the use of the shaver the blunt surfaces 33 of the combs grip the skin and hold it stationary, and the skin between the combs bulges into contact with the cutting head. Due to the eccentricities 18 on the slow speed shafts 8, the cutting head is given a circular motion having components lengthwise and transverse to the combs. Since the combs hold the skin stationary, the cutting head slides over the skin with a scanning action which exposes all of the skin surface between the combs to the slots in the cutting head. The relative movement of the cutting head is slightly greater than the pitch between the slots. In the present construction where the slots are .010" wide and the pitch between the slots is .020", it is sufficient that the cutting head be moved .030". The speed at which the cutting head is moved is limited by the sensitivity of the skin and should not exceed 3,000 strokes a minute. During the scanning movement of the cutting head the cutters 24 are being reciprocated at a much higher speed, from 7,000 to 10,000 strokes a minute, and co-

operate with the inner surface of the cutting head to shear hair projecting through the slots 22. Since the eccentrics move the cutting head transverse to the rocker arms 14, it is necessary that the rocker arms have laterally flexible sections 34 which permit lateral movement of the cutters so as to maintain the cutters in alignment with the head. This lateral movement does not interfere with the cutting action since the cutters are guided on the sides of the cutting head.

With the scanning movement of the head, the operator does not have to move the head repeatedly over the skin surface since the entire surface is covered in a single pass.

In addition to the shaving which takes place at the center of the cutting head, there is also a clipping action due to the movement of the cutting head relative to the combs 29. This clipping action clips the outer ends of the hair so the shorter lengths will be more readily shaved. As shown in Fig. 1, the slots 22 extend part way down the side walls of the cutting head to provide a clearance for the longer hair.

What I claim as new and desire to secure by Letters Patent of the United States is:

1. In a shaver, spaced skin-gripping members, a cutting head between said members having an outer skin-engaging surface and an inner shearing surface, hair-receiving openings in said head, means for effecting a slow speed relative movement between the head and the gripping members whereby the hair-receiving openings scan the skin surface between the gripping members, and a high speed cutter cooperating with the inner surface of the head to shear hair projecting through said openings.

2. In a shaver, an elongated skin-gripping member, an adjacent cutting head having an outer skin-engaging surface and an inner shearing surface, hair-receiving openings in said head, 40

means for effecting the slow speed relative movement between the head and the gripping member, both lengthwise and transverse to the gripping member whereby the hair-receiving openings scan the skin surface held by said gripping member, and a high speed cutter cooperating with the inner surface of the head to shear hair projecting through said openings.

3. In a shaver, an elongated skin-gripping member, an adjacent cutting head having an outer skin-engaging surface and an inner shearing surface, hair-receiving openings in said head, slow speed eccentrics cooperating with the head to move it lengthwise and transverse to the gripping member whereby the head scans the skin surface held by said gripping member, and a high speed cutter cooperating with the inner surface of the head to shear hair projecting through said openings.

4. In a shaver, an elongated cutting head having an outer skin engaging surface, an elongated skin gripping member having spaced teeth defining hair receiving openings, the outer surfaces of the teeth being arranged to grip the skin and the inner surfaces of said teeth overlapping and bearing against part of the outer surface of the cutting head, means for effecting a slow speed movement of the cutting head relative to the gripping member whereby the part of the outer surface of the cutting head engaging the teeth of the gripping member is effective to clip hair received in the openings between the teeth and the remaining part of the outer surface of the cutting head scans the skin surface held by said gripping member, and a high speed cutter cooperating with the inner surface of the cutting head to shear hair projecting through the openings in said remaining part of the head.

ADALBERT ALEXAY.
